UNITED STATES PATENT OFFICE

109,713

DESIGN FOR A BATHTUB

Julia L. Houston, Los Angeles, Calif.

Application March 11, 1938, Serial No. 75,757

Term of patent 14 years

To all whom it may concern:

Be it known that I, Julia L. Houston, a citizen of the United States, residing in Los Angeles, in the county of Los Angeles and State of California, have invented a new, original, and ornamental Design for a Bath Tub, of which the following is a specification, reference being had to the accompanying drawing, forming part thereof.

I claim:

The ornamental design for a bath tub substantially as shown.

JULIA L. HOUSTON.
